CYLINDER PRESS

Henry J. Hanauer, Milwaukee, Wis.

Application April 2, 1937, Serial No. 134,555

5 Claims. (Cl. 101—409)

This invention relates to improvements in cylinder presses, and more particularly to a cylinder die-cutting or printing press of the type which handles cardboard sheets for cut-outs, display cards, and the like.

There are several types of cylinder die-cutting or printing presses in general usage, but the same are open to certain objections. In the form of press under consideration sheets of material 10 are individually, successively fed to the cylinder to be operated on thereby when the sheet is carried by the cylinder to the lowest point of travel. An operator is required to feed the sheets to the cylinder from a large stack adjacent the feed 15 side of the cylinder and another operator is required to remove the cut or printed sheet from the cylinder at a discharge point and to arrange said operated on sheets in stacks.

In the single revolution cylinder press in quite 20 general usage the feed and discharge of sheets relative to the cylinder is on the same side of the machine. Obviously, this arrangement has disadvantages and interferes with efficient and economical production because the operators for the 25 fed and discharged sheets are at the same station and may bother each other, and there is also apt to be interference and confusion respecting the stacks of sheets wherein the sheets to be fed must be maintained free of the finished sheets.

30 Another type of cylinder press is that in which the cylinder moves through substantially one and one-half revolutions between the period of sheet engagement and sheet discharge. This machine has the advantage of permitting discharge 35 of a sheet on the side opposite the feed side, but it is very complicated, must be run at very high speeds for economical production, and requires extra engagement or contact with the sheet which in the case of heavy board is apt to be injurious thereto.

With the foregoing in mind it is, therefore, the primary object of the present invention to provide a cylinder die-cutting or printing press which is only turned one revolution for each 45 sheet operated on thereby, but which is arranged so as to discharge sheets on the opposite side of the cylinder from which the sheets are fed thereto giving so-called "straight-line" production and making for efficient, economical and expeditious production.

In the prior types of cylinder presses heretofore referred to, each sheet is engaged against the cylinder surface by a set of resilient fingers which are projected so as to grip an end portion of a sheet, with the sheet being held between the fingers and the cylinder surface. To insure the proper engagement of a sheet it must be fed at a tangent to the cylinder and in order that the sheet feed will not be at too great an inclination 55 so as to effect tangential disposition of the sheets,

it has been most practical, heretofore, to feed the sheets to the cylinder near or at the top thereof, although it is recognized that a lower point of feeding would be more advantageous.

It is therefore, another object of the present 5 invention to provide a cylinder press having grippers of a character which do not require the sheets to be fed to the cylinder at a tangent thereto, whereby the sheet feed may be near the lower portion of the cylinder without requiring 10 a feed platform disposed at an undue or inconvenient angle.

A further object of the invention is to provide a cylinder press of the character described having projectile and retractile grippers formed with 15 sheet engaging dogs and resilient fingers, a sheet being fed between bosses on the dogs and the fingers, and said bosses having surfaces which provide a tangential engagement for the incoming sheets, notwithstanding the fact that the 20 sheets are not disposed tangentially to the cylinder.

A further object of the invention is to provide a cylinder press of the class described in which the sheet is actually engaged by the cylinder for 25 substantially less than half of the revolution of the cylinder, minimizing the danger of the sheet being cracked or otherwise damaged by the cylinder and increasing the productivity of the machine without having it operate at an excessive 30 speed.

A further object of the invention is to provide a cylinder press of the character described wherein the sheet grippers retract into the cylinder adjacent the platen so as not to interfere 35 with operations on the sheet.

A further object of the invention is to provide a cylinder die-cutting or printing press which is of very simple construction, is strong and durable, is efficient in operation, and is well adapted 40 for the purposes set forth.

With the above and other objects in view, the invention consists of the improved cylinder press, and its parts and combinations as set forth in the claims and all equivalents thereof.

In the accompanying drawings in which the same reference characters indicate the same parts in all of the views:

Fig. 1 is a fragmentary end view of the improved cylinder press in one position during its cycle of operation, parts being broken away and in section;

Fig. 2 is a similar view only showing the cylinder in another position during its cycle of 55 movement;

Fig. 3 is a fragmentary end view showing the cylinder in still another position;

Fig. 4 is a fragmentary, detail sectional view indicated by the line 4—4 of Fig. 2 with certain 60

portions of the mechanism broken away to show details of construction;

Fig. 5 is an enlarged, fragmentary, detail sectional view taken on line 5—5 of Fig. 4 with certain associated parts shown in broken lines; and

Fig. 6 is a similar view only showing the release of a sheet from the sheet feed for engagement by the sheet grippers.

Referring now more particularly to the drawings, it will appear that the numeral 10 indicates an elevated table over which there is transversely mounted an elongated press cylinder designated generally by the numeral 11. Said cylinder has a central hub 12 forming an axis, and said hub tightly engages an operating shaft 13. The shaft is journaled in bearing brackets 17 outwardly of the ends of the cylinder and is turned by any conventional means (not shown) whereby the cylinder 11 may be revolved at a desired speed. The outer wall 14 of the cylinder is of circular contour and is spaced from the hub and shaft. The interior of the cylinder is hollow save for certain mechanism therein and radial spokes 15 extending from inner surface portions of the wall 14 to the hub 12. The ends of the cylinder are closed by heads or drums 16.

The cylinder 11 is adapted to revolve in the direction indicated by the arrows in the drawings and the lowermost portion of the wall 14 is spaced slightly from a cutter line or platen 18 provided on the table 10. In the exemplification illustrated the machine performs die-cutting operations on cardboard sheets and for that purpose blocks of cutters or knives 19 are mounted in the platen. It is obvious, however, that the platen may hold blocks of type in lieu of the cutters, if the machine is to be used as a printing press.

The outer wall 14 of the cylinder is formed with a relatively wide slot 20 extending through a portion thereof and longitudinally. Mounted within the cylinder so as to spacedly overhang said slot are a plurality of spaced-apart arms 21 which are secured at their inner ends to adjacent spokes 15. For rocking attachment to the outer end of each arm 21 there is provided a cupped member 22. The top of each cupped member is slotted, as at 23, to receive the end portion of its arm 21, and an elongated shaft 24 extends through and joins the respective cupped members 22 and arms whereby each cupped member is free to rock or oscillate on the shaft, and the shaft is supported by the arms.

Each of the cupped members has a recess 25 to receive one end portion of a coiled spring 26. The other end portion of each spring is mounted in a recess 27 in the side of an eccentrically shaped dog or gripper 28. All of said dogs are bifurcated and are rockingly mounted loosely on another shaft 29 secured within the cylinder and inwardly of the wall slot 20, and said dogs or grippers yieldingly extend or retract relative to said slot so as to project or retract gripping bosses 30 through said slot. Within the bifurcation of each gripper and loose with respect thereto, but fast on the shaft, so as to rock independently of or with the gripper is the inner end portion of a plate 31 which projects from said shaft toward and through the slot 16 and carries on its outer edge a spring metal element 32 having its free end slightly spaced from and cooperating with the gripper boss 30 in the engagement of the end of a cardboard sheet 33. The sheet engaging face of a boss 30 is parallel or tangent to the sheet 33. Although there is illustrated 75 and described a plurality of aligned gripping in-

strumentalities, it is obvious that a single elongated gripping member may be utilized.

Adjacent one side of the lower portion of the cylinder outer wall 14 there is an inclined feed guide 34 which is rigidly mounted on a suitable portion of the table 10. Said feed guide terminates adjacent the cylinder and is substantially tangential to the projected gripping faces of the gripper bosses 30. Secured to the underside of the lower end portion of the feed guide are a plurality of spaced-apart card stop fingers 35. Said fingers project beyond the end of the feed guide and are yieldable. The extremities of said fingers have upstruck angular flanges 36. Also secured to the underside of the feed guide and projecting beyond the lower end of the same are a plurality of card supporting fingers 37 having downwardly curved extremities 37'. Said fingers 37 are spaced-apart and are spacedly interposed between the stop fingers 35. Normally the upper faces of the fingers 37 are slightly below the planes of the upper edges of the stop fingers 35, so that a card 33 resting on the fingers 37 will have its forward end in abutment with the flanges 36, as in Figs. 3 and 5. However, means are provided for downwardly flexing the stop fingers 35 so as to remove the flanges 36 from engagement with the card end to permit forward feeding of the card to the cylinder.

From the drawings it will be observed that one end of the cylinder 11 carries a curved cam plate 38 which extends only partially about the circumference of the cylinder wall 14. A cam roller 39 is adapted to ride on the cam plate and to drop therefrom and onto the wall 14 and to then ride back onto the cam plate during a revolution of the cylinder. Said cam roller is journaled on the outer end of an arm 40 whose other end is fast on a shaft 41 which is journaled for oscillatory movements in brackets 42 depending from the sheet feed 34. The shaft 41 extends transversely of the sheet feed and fingers 35 and 37 and is immediately above the fingers 35. Adjacent each finger 35 the shaft has a flattened portion 43 which permits normal disposition of said fingers, but when the shaft is turned so as to contact its rounded portions with said fingers, said fingers 35 will be depressed or flexed downwardly as previously mentioned and as shown in Figs. 1, 2 and 6.

In the operation of the improved cylinder press the feed operator stands at the front of the cylinder (the right side thereof in the drawings) and the discharge operator stands at the rear of the cylinder (the left side thereof in the drawings), and hence the respective operators do not interfere with one another, and the pile of sheets to be fed to the press are maintained separately and out of the way of the pile of discharged completed sheets. It is also obvious that the cylinder press insures so called "straight line production", and a sheet is engaged by the cylinder for only a portion of the revolution of the cylinder, the same being engaged by the cylinder on one side adjacent the bottom thereof, and being discharged by the cylinder when it moves through less than one half of a revolution.

Assuming that the cylinder revolves in the direction indicated by the arrows in the drawings and that the cam plate 38 has passed the sheet 70 feed 34, it will be evident that the apparatus is in condition to have a sheet fed into position. This condition is illustrated in Figs. 3 and 5 wherein the cam roller 39 is riding on the cylinder wall 14 and the fingers 35 are in their normal raised 75

positions so that the forward edge of the sheet 33 is stopped by the upturned flanges 36 of said fingers 35. Upon subsequent turning of the cylinder 11 just as the projecting grippers 28 come into position adjacent the lower end of the sheet guide, the cam roller 39 will ride upon the cam plate 38, whereupon the shaft 41 will be turned so that its rounded portions will ride on the faces of the fingers 35 and depress the same to the position of Figs. 1 and 6, permitting the sheet 33 to be pushed beyond the sheet guide and into the grippers 28, the end of the sheet being engaged between the resilient plates 32 of the grippers and the bosses 30, as in Fig. 1. Said plates 32 are on the shaft 29 which is cam actuated and have at this point been swung from an inoperative position to the sheet engaging position of Fig. 1. The grippers are of course urged outwardly through the cylinder slot 16 by the springs 26, and outward movement of the grippers is limited by the shoulders 44 thereon which abut against the inner surface of the end portion of the wall 14. It will thus be seen that the sheet 33 is initially engaged by the grippers in the manner depicted in Fig. 1. The cylinder then continues its movement toward the position shown in Fig. 2, and as the grippers reach their lowermost position they contact with the platen 18 and are yieldingly retracted inwardly, as shown, against the tension of the springs 26, but at the same time maintaining engagement with the end of the sheet and drawing it from the sheet feed into contact with the face of the cylinder wall 14. Hence, upon further turning of the cylinder the sheet will be pressed between the cylinder wall 14 and the instrumentalities on the platen 18 and will be die-cut or printed upon. After the cylinder turns so as to free the gripper of contact with the platen, the same will project further outwardly, and at the discharge side of the cylinder the shaft 29 is cam actuated so as to remove the plates 32 from gripping engagement with the bosses 30 and the operator is free to remove the cardboard from the cylinder after it has passed beyond the platen or dies. After the cylinder has turned through one half of its revolution the cam roller 39 drops from the cam plate 38 onto the wall 14 and permits the fingers 35 to spring upwardly to the Figure 3 position so as to stop another cardboard sheet fed thereto for subsequent operations. It will be obvious that the grippers are free to project or retract relative to the cylinder wall slot 16 and to rock on the shaft 29. The same are, however, urged outwardly by the coiled springs 26 and only retract into the cylinder upon engagement with the platen or dies so as not to interfere with the same nor to be an obstacle or obstruction. The members 22 are also free to rock on their shaft 24.

From the foregoing description it will be seen that the improved cylinder press provides for straight line production and receives sheets fed thereto on the side opposite from which the sheets are discharged. The sheets are engaged by the cylinder for only a portion of the travel of the cylinder, and therefore the danger of the same being bent or cracked by the cylinder is minimized. The press is simple, makes for fast and efficient production without being run at excessive speeds, and is well adapted for the purposes set forth.

What is claimed as the invention is:

1. In a cylinder press, a revoluble cylinder hav-

ing a circular sheet engaging wall with an opening therein, a plurality of arms rigidly mounted within the cylinder, a shaft carried by said arms, rocker elements mounted on said shaft, another shaft within the cylinder, rigid sheet gripping dogs rockingly mounted on said latter shaft so as to move relative to said wall opening, resilient members carried by the dogs and coacting with portions thereof, and resilient connections between the dogs and the rocker elements.

2. A cylinder press, comprising a revoluble cylinder having an annular sheet engaging wall formed with an opening therein, a gripping device movably mounted within the cylinder and normally projected a substantial amount through said wall opening, projected portions of the gripping device including a boss having its work face at a secant to the cylinder wall when said device is in its fullest projected position and also a coacting spring finger, said boss and finger engaging a sheet fed at a secant to the cylinder, and a platen in close proximity to a peripheral portion of the cylinder wall against which a sheet is pressed after being engaged by the gripping device, engagement of the gripping device with the platen retracting the former to a position wherein the plane of its work face is tangential to the cylinder wall.

3. In a cylinder press, a revoluble cylinder having a circular sheet engaging wall with an opening therein, an arm rigidly mounted within the cylinder, a shaft carried by said arm, a rocker element mounted on said shaft, another shaft within the cylinder, a rigid sheet gripping dog rockingly mounted on said latter shaft so as to move relative to said wall opening, a resilient member associated with the dog and coacting with a portion thereof, and a resilient connection between the dog and the rocker element.

4. In a cylinder press, a revoluble cylinder having a circular sheet engaging wall with an opening therein, a sheet gripping device movably mounted within the cylinder and including a boss, the boss being mounted within the cylinder so as to project or retract relative to the wall opening, said boss in projected position contacting a sheet fed non-tangentially to the cylinder, a coacting gripper finger movably mounted relative to the boss to engage a sheet at the time of contact of the sheet with the boss, and retracting means acting upon the boss and the finger to bring the gripped sheet into tangential relation to the circular wall of the cylinder.

5. In a cylinder press, a revoluble cylinder having a circular sheet engaging wall with an opening therein, a sheet gripping device movably mounted within the cylinder and including a plurality of spaced bosses, said bosses being mounted within the cylinder so as to simultaneously project or retract relative to the wall opening, said bosses in projected position contacting a sheet fed non-tangentially to a lower portion of the cylinder, coacting gripper fingers movably mounted relative to the bosses to engage a sheet at the time of contact of the sheet with the bosses, and retracting means acting upon the bosses and fingers upon further movement of the cylinder to bring the gripped sheet into tangential relation to the circular wall of the cylinder.

HENRY J. HANAUER.
